UNITED STATES PATENT OFFICE.

PAUL HARIVEAU, OF PARIS, FRANCE.

SELF-PRIMING CENTRIFUGAL PUMP.

Application filed May 17, 1923. Serial No. 639,653.

To all whom it may concern:

Be it known that I, PAUL HARIVEAU, a French citizen, residing in Paris, in the Republic of France, have invented certain new and useful Self-Priming Centrifugal Pumps, of which the following is a specification.

This invention relates to new and useful improvements in self-priming centrifugal pumps.

The object of the present invention is to provide a priming arrangement applicable to a centrifugal pump having two inlets that is to say including two pipes through one of which air is sucked up and through the other the liquid to be pumped.

To carry out the priming arrangement of the invention, the pump having two suction pipes has one of these pipes connected to a suction immersed in the pit and the other to a priming reservoir filled with water, the said reservoir being also connected on the other hand to the delivery pipe of the pump.

Under these conditions the rotor of the pump which is provided with two blades placed side by side causes by its splashing in the water the priming of the blade on the reservoir side and then the pumping of air into the suction pipe, that is to say the priming of the pump which is thus produced automatically each time it is set in operation.

This invention will now be described with reference to the accompanying drawings, in which:—

Fig. 1 is a view in elevation of the pump provided with the priming arrangement according to the invention, in section on the line A—A of Fig. 2, Fig. 2 is a section taken at right angles on the line B—B of Fig. 1.

Referring to the figures it will be seen that the rotor 1 of the pump is provided with a central imperforate disk having two series of blades 2 and 3 covered by cheeks 4 and 5 and mounted on opposite sides of the disk within separate compartments 35, 36. The hub 6 forming the disk between the two series of blades is keyed on the shaft 7 which passes through the two covers 8 and 9 which carry respectively two suction pipes 10 and 11. The rotor 1 is surrounded by a volute 12 which is terminated by the delivery pipe 13 of the pump. The suction pipe 11 is connected with the suction conduit 14 which dips into the pit 15. The suction pipe 10 is connected with a reservoir 17, be-

tween which a diaphragm 16 is interposed, at the point where a seat 18 is formed against which a closing plug 19 bears. The latter is supported by a lever 20 movable about a shaft 21 and actuated by a float 22 connected with the lever 20 by a pipe 23 guided on a rod 24.

The discharge pipe 13 of the pump is fixed to a T-pipe 25 which connects the delivery pipe 26 with the reservoir 17 which is provided at the point of connection with a perforated boss 27 the lower part of which is at the same level as the lower part of the shaft 7.

On the side of the reservoir a priming tap 28 is fixed having a funnel 29, the upper part 30 of which is also at the same level as the point 31 situated at the lower part of the shaft.

The working of the pump according to this invention is as follows:—

Before the first operation which serves for all further operation the priming tap 28 is opened and the necessary quantity of water is poured through the funnel 29, to attain in the pump the reservoir and the funnel the level 27, 30, 31, 32. The tap 28 is then closed. At this moment owing to the level of the float 22 the plug 19 is lowered off its seat 18 and the pump is started. Under the splashing action of the rotor 1 in the water a portion of this water is thrown into the volute 12 and escapes through the T-pipe 25 to fall back into the reservoir 17. The water contained in the lower part of the wheel being thrown towards the periphery produces at each of its inlet apertures a high suction effect which extends into each of the suction pipes 10 and 11. The suction in the suction pipe 10 causes the water to rise from the reservoir 17 into this pipe 10 so that almost immediately the series of blades 2 of the rotor 1 which corresponds with the suction pipe 10, pumps water from the reservoir 17 in order to throw it back into the same reservoir by the discharge pipe 13 and the T-pipe 25. The water spray which is produced in the compartment 35 causes in the compartment 36 suction of air from the suction conduit 14 connected with the suction pipe 11. The water from the pit 15 rises in the suction pipe 14 until it reaches the entrance of the wheel 1 into the compartment 36 housing the blade 3 which discharges the water from the pit into the reservoir 17.

thus causing the float 22 to rise and at a predetermined moment the closure plug 19 to abut against the seat 18. From this moment the pump which was effectively primed as soon as the water from the suction pipe had reached the blades 3 of the wheel 1 is in a condition to furnish its required pressure and its maximum output into the delivery pipe 26. During the priming the air drawn into the suction pipe 14 and forced into the reservoir 17 is discharged through the exit aperture 26 passing through the pipe 33 arranged at the highest part of the reservoir 17.

When the device stops, owing to the bent swan's neck arrangement of the suction pipe 14 at its connection with the suction pipe 11, the maximum level which the water can take corresponds to the upper part of the entrance diameter of the wheel 1 at the point 34 as above this level water would return to the pit by siphonic action. At this maximum level the plug 19 is at a suitable distance from its seat 18. If any stuffing box during a long period of inactivity of the pump allows water to escape, the latter falls to a level which can not be lower than the level 27, 30, 31, 32, that is to say the level which is necessary and sufficient to enable the apparatus to work properly.

When the pump draws water from a well it may happen that the quantity of water drawn up by the pump in a given time is greater than the quantity of water furnished by the source which feeds the well and in due course the lower end of the pipe 14 will be uncovered by the water. The pump will then suck in air thus placing itself automatically in a priming position. As soon, however, as the level of the water in the well has risen and covers the lower end of the pipe 14 the pump continuing to suck air will produce a depression which will cause the water again to rise in the pipe 14 and the pump will be automatically re-primed.

When the pump is primed and working normally the valve 19 is pressed on its seat and the left hand blades 2 become inoperative. As a special utilization of this pump a valve controlled pipe (not shown) communicating with a reservoir in which it is desired to produce a vacuum may be connected with the pipe 10. Another possible way of utilizing a pump furnished with this priming arrangement consists in drawing air by the blades 2 through the pipe 10 at a point open to the atmosphere whilst the blades 1 draw water and delivering the mixture of water and air into a closed reservoir. The water is then under pressure in consequence of the compressed air above it and water may thus be delivered under pressure.

In both cases the blades 3 of the wheel 1 pump up water and the blades 2 of the wheel 65 pump in air.

In the first case the mixture of air and water is forced to the outside at atmospheric pressure.

In the second case the mixture of air and water is forced under pressure into the reservoir utilized for ensuring the distribution of water under pressure by compressed air.

The means which have been found most suitable for carrying out the priming arrangement according to the invention have been described but it is of course evident that the invention is not limited to the exact details of construction and that others fulfilling the same functions may be substituted therefor.

I declare that what I claim is:—

1. In a priming device for centrifugal pumps for fluids the combination of a pump casing, a rotor mounted within said casing, a pair of inlet pipes, means to connect one of said inlet pipes to the supply fluid, a priming reservoir, means to connect the other of said inlet pipes with said priming reservoir, a valve on said pipe between said priming reservoir and said inlet pipe and means to control automatically, the flow of fluid between said priming reservoir and said inlet pipe.

2. In a priming device for centrifugal pumps for fluids the combination of a pump casing, a rotor mounted within said casing, a pair of inlet pipes, means to connect one of said inlet pipes to the supply fluid, a priming reservoir, means to connect the other of said inlet pipes with said priming reservoir, a valve on said pipe between said priming reservoir and said inlet pipe and a float in said reservoir adapted to control automatically the position of said valve when the liquid therein has reached a predetermined level.

3. In a priming device for centrifugal pumps for fluids the combination of a pump casing, a rotor mounted within said casing, a pair of inlet pipes, means to connect one of said inlet pipes to the supply fluid, a priming reservoir, means to connect the other of said inlet pipes with said priming reservoir, a valve on said pipe between said priming reservoir and said inlet pipe, a float in said reservoir adapted to control automatically the position of said valve when the liquid therein has reached a predetermined level, a delivery pipe and means to connect said priming reservoir with said delivery pipe.

4. In a priming device for centrifugal pumps for fluids the combination of a pump casing, a rotor mounted within said casing, a pair of inlet pipes connected with said casing, a priming reservoir, means to connect one of said pipes with said priming reservoir, means to control automatically the flow of liquid through said connection, and connecting means between said other inlet

pipe and the liquid to be pumped including a swan neck connection, in order to cause the water within the pump to take up a predetermined level.

5. In a centrifugal pump having a casing and a rotor therein with an imperforate central disk and impeller blades on both sides of said disk, an inlet pipe to lead the supply fluid to one side of said rotor disk, a priming reservoir, a second pipe leading from
- 10 said reservoir to the other side of said rotor

disk, a delivery pipe leading from said casing, and a by pass pipe from said delivery pipe to said reservoir, whereby one side of said disk and its impeller blades acts to 15 maintain the priming of the pump and the other side and its impeller blades acts to pump the supply fluid.

In witness whereof, I have hereunto signed my name this 28 day of March 1923.

PAUL HARIVEAU.
